Primary Examiner — Selina Sikder(74) *Attorney, Agent, or Firm* — Jenkins, Wilson, Taylor & Hunt, P.A.(57) **CLAIM**

The ornamental design for a light emitting device package, as shown and described.

DESCRIPTION

FIG. 1 is a perspective view of a light emitting device package showing our design;

FIG. 2 is a top view thereof;

FIG. 3 is a front side view thereof, the opposing rear side view being a mirror image of that shown;

FIG. 4 is a right side view thereof;

FIG. 5 is a left side view thereof;

FIG. 6 is a bottom view thereof; and,

FIG. 7 is a bottom perspective view thereof.

The dashed broken lines are for illustrative purposes only and form no part of the claimed design.

APPLICATION NO. : 29/403433
DATED : June 5, 2012
INVENTOR(S) : Joo et al.

Page 1 of 1

It is certified that error appears in the above-identified patent and that said Letters Patent is hereby corrected as shown below:

On the title page, item 54 and col. 1, line 1,
replace "LIGHT EMITING DEVICE PACKAGE"
with --LIGHT EMITTING DEVICE PACKAGE--.

Signed and Sealed this
Seventh Day of August, 2012

David J. Kappos
Director of the United States Patent and Trademark Office
